DESIGN FOR A TEXTILE FABRIC

Murray A. Opolinsky, New York, N. Y.

Application March 7, 1936, Serial No. 61,515

Term of patent 3½ years

To all whom it may concern:

Be it known that I, Murray A. Opolinsky, a citizen of the United States of America, residing in Manhattan, county of New York and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

In the drawing the design unit is indicated within the dotted lines A—B—C—D.

I claim:

The ornamental design for a textile fabric, substantially as shown and described.

MURRAY A. OPOLINSKY.
